(57) **CLAIM**

I claim the ornamental design for an outdoor lighting structure, as shown and described.

DESCRIPTION

FIG. 1 is a perspective view of an outdoor lighting structure showing the new design thereof;

FIG. 2 is a top plan view thereof;

FIG. 3 is a front side elevational view thereof;

The left side elevational view, the right side elevational view, and the rear side elevational view are the exact same as the front side elevational view.

FIG. 4 is a perspective view of an alternate embodiment for the outdoor lighting structure thereof;

FIG. 5 is a top plan view of the alternate embodiment thereof;

FIG. 6 is a front side elevational view of the alternate embodiment thereof.

FIG. 7 is a left side elevational view of the alternate embodiment thereof.

The right side elevational view of the alternate embodiment is a mirror image of the left side elevational view; and,

FIG. 8 is a rear side elevational view of the alternate embodiment thereof.

The broken lines for the outdoor lighting structure throughout FIGS. 1 through 8 are for illustrative purposes only and form no part of the claimed design.
